Application September 2, 1949, Serial No. 113,845

27 Claims. (Cl. 187—29)

1

This invention relates to multi-car elevator systems, and it has particular relation to dispatchers for dispatching elevator cars at suitable intervals from a dispatching floor.

Elevator dispatchers may be of the rotational or non-rotational type. A rotational dispatcher for a bank of elevator cars dispatches elevator cars from a dispatching floor in a predetermined invariable order. The order of arrival of cars at the dispatching floor has no effect on the order in which the cars are dispatched in the rotational dispatching system. A non-rotational dispatcher dispatches elevator cars from the dispatching floor substantially in the order of arrival of the cars at the dispatching floor. Although aspects of the invention may be employed in a rotational dispatcher, the invention is particularly suitable for the non-rotational dispatcher and will be discussed with respect to a non-rotational dispatcher.

The demand for elevator service is subject to substantial variation throughout the day. If the dispatching interval of an elevator dispatcher is selected for a predetermined service demand, any variation in the service demand may result in a bunching of the elevator cars at the dispatching or other floors and may result in poor service to intending passengers.

In accordance with the invention, an elevator dispatcher has a dispatching interval which is selected for a predetermined service demand. For example, the interval may be selected to provide suitable service under conditions of a heavy demand for service from intending passengers. However, the dispatch of elevator cars from the dispatching floor is expedited under certain conditions.

Let it be assumed that the dispatching interval is selected for a heavy service demand and that it represents a comparatively long time value. As long as the heavy service demand continues, a car arrives at the dispatching floor as each preceding car at the dispatching floor is dispatched. Substantially only one car is present at the dispatching floor under these conditions.

If the demand for elevator service decreases, cars will tend to accumulate at the dispatching floor. However, in response to the accumulation of a predetermined number of cars at the dispatching floor, the dispatching interval for the next car to be dispatched is decreased from the aforesaid long value to a medium value of time. Following the dispatch of a car upon the expiration of a medium dispatching interval, succeeding cars again are dispatched in accordance with long dispatching intervals until the pre-

2

determined number of cars again accumulates at the dispatching floor.

In the event that a number of cars greater than the predetermined number accumulates at the dispatching floor, the dispatching system automatically decreases the dispatching interval of the next car to be dispatched to a short value of time. The second car to be dispatched is dispatched after the expiration of the medium interval of time measured from the departure of the first car. The third and succeeding cars thereafter are dispatched in accordance with the long dispatching intervals.

The variable sequence of dispatching provided by the invention prevents excessive accumulation of cars at the dispatching floor and minimizes the possibility of the bunching of cars at any point in the system.

Preferably the next car to be dispatched from a dispatching floor is selected as promptly as possible after the arrival of the car at the dispatching floor. This enables the car attendant to open his doors and load his car while awaiting the expiration of his dispatching interval. A suitable signal may be given to each attendant for the purpose of notifying him that his car has been selected as the next car to be dispatched from the dispatching floor. At the same time a suitable signal such as a floor lantern may be actuated at the dispatching floor for the purpose of notifying intending passengers that the car adjacent the floor lantern will be the next car to leave the dispatching floor. Assuming that a car has been selected as the next car to leave the dispatching floor and that the dispatching interval for the car has expired, the car may be started in any suitable manner. For example a lamp may be illuminated in the car to indicate to the car attendant that he should start the car.

In some elevator installations the service demand in the two directions of travel of elevator cars may differ. For example the service demand for travel in the down direction may be substantially heavier than that for the up direction. In accordance with a further aspect of the invention, the dispatching intervals at either or both of the dispatching floors (usually the upper terminal floor and the lower terminal or street floor) may be adjusted independently or simultaneously in accordance with the difference in the service demand for the two directions of travel. Thus if the predominant demand is in the down direction, the cars may be dispatched with a shorter dispatching interval from the upper dispatching floor than that em-

ployed for the lower dispatching floor. If the predominant demand is in the up direction, the cars may be dispatched with shorter dispatching intervals from the lower dispatching floor.

Thus far the invention has been discussed with reference to a dispatching interval based on the positioning of the cars adjacent the dispatching floor. The invention further contemplates the adjustment of the dispatching interval in accordance with the positioning of the cars with respect to localized service demand areas other than the dispatching floors. For example the floors served by the elevator cars may be divided into zones or localized service areas. A service or call demand in excess of a predetermined value from intending passengers in any zone with no car in position to answer the service demand within a reasonable time expedites the dispatch of a car from the dispatching floor for the purpose of answering with reasonable promptness the service demand.

If desired, the system may be so arranged that the accumulation of a predetermined number of cars, such as three cars at a dispatching floor, immediately dispatches one of the cars from the dispatching floor. Should a service demand from any zone occur when no car is in position to answer the service demand within a reasonable period of time, a car is immediately dispatched from the dispatching floor when only two cars accumulate at such floor in order to aid in answering the service demand.

A still heavier service demand such as a service demand above a predetermined value from two zones with no car in position to answer the service demand within a reasonable time may further expedite the dispatch of a car from the dispatching floor. Under these circumstances a car may be dispatched immediately from the dispatching floor, even if it is the only car at the dispatching floor.

A similar dispatching system may be provided at each of the two dispatching floors. If the service demand is only in the down direction, the dispatching system here-in described may be employed only at the upper dispatching floor. However, whenever the dispatch of a car from the upper dispatching floor is expedited, a similar dispatching change is made at the lower dispatching floor.

The above discussion has been primarily with reference to service demand from the floors served by the elevator cars. The invention further contemplates expediting the dispatch of a car in response to a service demand above a predetermined value from the passengers within the car. Thus if the car attendant operates more than a predetermined number of car call buttons for the purpose of registering the floors to which his passengers desire to be carried while he is awaiting a start signal at one of the dispatching floors, his start signal may be expedited.

It is, therefore, an object of the invention to provide an improved elevator dispatching system which is responsive to service demand.

It is also an object of the invention to provide an elevator dispatching system wherein a plurality of successive dispatching intervals may be varied as a function of elevator cars accumulating at the dispatching floor.

It is an additional object of the invention to provide an elevator dispatching system wherein a car to be dispatched is selected promptly, and the dispatch of the car thereafter occurs after the expiration of a dispatching interval which is

a function of the accumulation of elevator cars adjacent the dispatching floor.

It is a further object of the invention to provide an elevator dispatching system wherein the dispatching interval varies as a function of the difference in service demand for the two directions of travel of the elevator cars.

It is another object of the invention to provide an elevator dispatching system wherein the dispatching interval is varied as a function of the localized service demand and the position of the elevator cars with respect to the localized service demand.

It is a still further object of the invention to provide an elevator system including an elevator dispatcher having a dispatching interval which varies as a function of service demand from passengers within the elevator cars.

Other objects of the invention will be apparent from the following description, taken in conjunction with the accompanying drawings, in which:

Figure 1 is a view in front elevation with parts broken away of an elevator system.

Fig. 2 is a schematic view in straight line form of an elevator dispatcher embodying the invention.

Fig. 2A is a schematic view of the relays employed in the system of Fig. 2. If Figs. 2 and 2A are placed in horizontal alignment, it will be found that the windings and contacts of the various relays are in horizontal alignment.

Fig. 3 is a schematic view of an adjustable resistor which is responsive to the difference in service demand for the two directions of travel of elevator cars.

Fig. 4 is a schematic view in straight line form showing additional circuits which may be employed in the elevator dispatching system.

Fig. 4A is a schematic view of the relays illustrated in Fig. 4. The windings and contacts of the relays of Figs. 4 and 4A may be brought into horizontal alignment in the manner discussed with reference to Figs. 2 and 2A, and

Fig. 5 is a schematic view of a typical floor call circuit.

The invention is applicable to banks of elevator cars containing various numbers of elevator cars. For the purpose of discussion, a system will be described with reference to a bank containing four elevator cars, but it is to be understood that it may be employed with banks having different numbers of elevator cars. The cars will be designated by the letters A, B, C and D, and components specific to the respective cars will be designated by the letter, A, B, C or D, followed by other suitable designating characters.

Relays are employed which may have "make" or "break" contacts. Make contacts of a relay interrupt a circuit as long as the relay is deenergized. Energization of the relay closes to make contacts. The break contacts of a relay are closed to complete an electrical circuit as long as the relay is deenergized. Energization of the relay opens its break contacts to interrupt a circuit. The various contacts of a relay are each identified by the reference character applied to the relay followed by a reference character specific to each set of contacts.

The relays specific to the car A are as follows:

AU—Upper terminal relay

AL—Lower terminal relay

AN—Next relay

AS—Auxiliary start relay

ACC—Car call expeditor

The following relays are common to all cars:

- 1S, 2S, 3S, K, IDU and IDL—Interval relays
- 2E and 3E—Expediter relays
- T, UT and LT—Auxiliary expediter relays
- US and LS—Start relays
- R0, R1, R2 and R3—Service demand relays
- P1, P2 and P3—Car position relays
- 2DR to 16DR—Floor down-call registering relays
- 1UR to 5UR—Floor up-call registering relays

FIGURE 1

In Fig. 1 car A is secured to a counterweight 1 through one or more flexible ropes or cables 3. The rope or ropes pass over a sheave 5 which is mounted on the shaft 7 of an electric motor 9. Brake mechanism 11 is provided for stopping the elevator car and for holding it in any desired position.

The motor 9 may be energized in any conventional manner for the purpose of moving the elevator car A in either of its two directions of travel between its terminal floors. It will be assumed that the elevator car is controlled by a car switch 13 which is closed to initiate movement of a car. After the car has started in movement, the car stops automatically at floors for which push buttons in the car, or push buttons for the various floors, have been actuated. It will be understood that the push-button station 15 for the car has one push button for each of the floors served by the elevator car. The elevator attendant actuates one of the push buttons for each of the floors at which the elevator car is to stop for the purpose of discharging passengers. Two floor push-button stations 17 and 19 are illustrated. The station 17 is located at the second floor and contains an up push button 2U and a down push button 2D. Similarly the station 19 is positioned at the third floor and has a down push button 3D and an up push button 3U. In accordance with common practice, each of the floor push-button stations is common to the entire bank of elevator cars.

Inasmuch as the mechanism for controlling the starting and stopping of the elevator car is well known in the art, a detailed description of such apparatus is believed to be unnecessary. Such apparatus may include a selector 21 which is responsive to the position of the car. For example the selector includes a stationary panel 23 of insulating material which carries several rows of contact segments. Two rows Aa and Ab are illustrated in Fig. 1. One of the contact segments in each of these rows is provided for each of the floors served by the elevator car.

The selector also has a movable carriage 25 which is moved in a vertical direction by means of a screw 27. The screw 27 is rotated by the shaft 7 through suitable gearing 29. The carriage 25 has a separate brush 31 or 33 for engaging successively the contact segments of each of the rows of segments.

In addition the selector may have additional contact segments for other control purposes. For example the panel 23 has a contact segment Ac which is engaged by a brush 35 on the movable carriage when the elevator car is at or adjacent to its upper terminal position. The panel 23 has an additional contact segment Ad which is engaged by a brush 37 when the elevator car is at or adjacent to its lower terminal floor. In Fig. 1 the carriage 25 is located below the lower terminal floor at a position which may correspond to the basement of a building served by the elevator car.

FIGURE 2

When a number of elevator cars are associated in a bank it is desirable that they be dispatched from one or more dispatching floors according to suitable schedules. In most installations of banks of elevator cars, the dispatching floors usually are the upper terminal floor and the first floor of the building served by the bank. It may be assumed that if the building has a basement, a special operation is necessary to move the elevator car below the first floor or dispatching floor to the basement. For the purpose of the present discussion it will be assumed that the elevator cars operate between the first floor which comprises the lower terminal or dispatching floor and the highest floor which serves as the upper terminal or dispatching floor.

It will be understood that similar dispatching equipment may be provided for each of the dispatching floors. With reference to Fig. 2, it will suffice to describe in detail the dispatching equipment associated with the upper dispatching floor.

As cars reach the dispatching floor, it is desirable that the next car to be dispatched from the floor be selected as promptly as possible. This enables the car attendant to fill his car as he waits for the expiration* of his dispatching interval. The selection of the next car to be dispatched is effected by selecting mechanism which is operated in part by a constant speed motor 39. This motor is releasably coupled to a cam 41 by means of an electromagnetic clutch RC. When the winding of the clutch RC is de-energized, the motor 39 is disconnected from the cam 41. When the winding is energized, the motor is connected to the cam 41 and rotates the cam for the purpose of selecting the next car to be dispatched from the dispatching floor.

Energization of the electromagnetic clutch RC is controlled in part by upper terminal relays AU, BU, CU and DU. For example when the elevator car A is at or adjacent its upper terminal, the brush 35 engages the contact segment Ac to connect the winding of the upper terminal relay AU across the buses L1 and L2 which represent a source of direct current. When the upper terminal relay AU is energized, it closes its make contacts AU1 and AU2. In closing, the contacts AU2 prepare the winding of the next relay AN for subsequent energization.

Closure of the make contacts AU1 completes an energizing circuit for the electromagnetic clutch RC as follows:

L1, AU1, RC, AN1, BN1, CN1, DN1, L2

If some car of the bank has already been designated as the next car to leave the dispatching floor, one of the sets of the break contacts AN1, BN1, CN1 or DN1 will be open to prevent energization of the electromagnetic clutch RC. It will be assumed, however, that no car has been so designated and that the electromagnetic clutch RC is energized upon arrival of the car A at the upper dispatching floor.

As the cam 41 rotates, it closes successively the switches AY, BY, CY and DY. This continues until the cam closes the switch of a car located at or adjacent the dispatching floor. Thus when the cam closes the switch AY, a circuit is completed for the next relay AN:

L1, AU2, AN, AS4, AY, L2

Had any of the other switches BY, CY or DY been closed, the associated next relays BN, CN,

DN would have remained deenergized for the reason that the cars B, C and D are assumed to be away from the upper dispatching floor, and the contacts BU2, CU2 and DU2 are open.

When the next relay AN is energized, it opens its break contacts AN1 and closes its make contacts AN2 and AN3. The opening of the break contacts AN1 deenergizes the winding of the electromagnetic clutch RC, and the cam 41 consequently stops rotating. The selecting mechanism cannot be operated again until the break contacts AN1 have been reclosed.

In closing, the contacts AN2 prepare the relay AS for subsequent energization.

Closure of the make contacts AN3 completes the selection of the car A as the next car to be dispatched. The closure may be employed in various ways for completing the selection. In the specific embodiment herein illustrated, closure of the contacts AN2 illuminates a next signal lamp ANL through the circuit:

L1, AN3, AS2, AHL, ANL, L2

The next signal lamp ANL is located on the car A and informs the attendant that his car has been selected as the next car to leave the dispatching floor. Consequently the car attendant can proceed to load his car. It should be noted that this selection is effected rapidly.

Closure of the next relay can be employed for other functions. For example such closure may be employed for illuminating hall lanterns at the dispatching floor to indicate to intending passengers which car had been selected as the next car to leave the dispatching floor. Such a hall lantern AHL may be connected in parallel with the lamp ANL, but is shown in Fig. 2 connected in series with the signal lamp ANL. Similar hall lanterns may be connected in series respectively with the next signal lamps of the remaining cars.

The dispatching system also "starts" each of the cars from the dispatching floor after the expiration of a suitable dispatching interval. In the system herein discussed the dispatching system may be said to "start" a car by notifying the car attendant that he should leave the dispatching floor. To this end the motor 39 is releasably coupled to a timer cam 43 through an electromagnetic clutch SC. The winding of this clutch is energized through the circuit:

L1, IS1, SC, AS1, BS1, CS1, DS1, L2

When the winding is energized, the cam 43 is actuated away from a starting position to operate a cam-operated switch S. When the electromagnetic clutch is deenergized, a spring 45 returns the cam 43 to its starting position. The construction of the motor 39 and the electromagnetic clutches may be similar to that illustrated in the Eames Patent 2,121,527.

Each of the contacts AS1, BS1, CS1 and DS1 opens when its associated car is ordered to start from the dispatching floor. Until contacts AS1, BS1, CS1 and DS1 are all closed, the electromagnetic clutch cannot be energized and a succeeding timing interval cannot be initiated.

When the timing cam 43 reaches the switch S, the switch contacts close to energize the interval relay IS through the circuit:

L1, IS, S, AS1, BS1, CS1, DS1, L2

The interval relay IS opens its break contacts IS1 and IS4, and closes its make contacts IS2 and IS3. The contacts IS2 establish a holding

circuit around the switch S. The contacts IS1 in opening deenergize the winding of the electromagnetic clutch SC, and the spring 45 promptly restores the timing cam to its starting position. The contacts IS3 control in part the energization of the expeditor relays 2E and 3E. The contacts IS4 in opening deenergize the interval relay 2S. This relay has a time delay in dropout which is determined in any suitable manner as by a resistor 47 which is connected across the winding of the relay 2S. The resistance value of the resistor 47 may be adjustable to permit adjustment of the dropout time of the interval relay 2S.

It will be understood that the interval relay 2S normally is energized. When the contacts IS4 open and interval relay 2S times out, it opens its make contacts 2S1 and closes its break contacts 2S2. Closure of the break contacts 2S2 has no effect on the operation of the system as long as the expeditor relay 2E remains deenergized and contacts 2E1 remain open.

Opening of the contacts 2S1 deenergizes the normally-energized interval relay 3S. The relay 3S also has a time delay in dropout. The time delay may be obtained in any suitable manner as by means of a resistor 49 which is connected across the winding of the time interval relay 3S.

Upon the expiration of the time delay of the relay 3S, it drops out to close its break contacts 3S1. This completes the following circuit for the start relay US:

L1, 3S1, US, L2

Thus the dispatch interval required for energizing the start relay US is the sum of the delays introduced by the switch S and the relays 2S and 3S.

When energized, the start relay US closes its make contacts US1. If a car is adjacent a dispatching floor (contacts AU2, BU2, CU2 or DU2 are closed) and if one of the cars at the dispatching floor has been selected as the next car to be dispatched (contacts AN2, BN2, CN2 or DN2 are closed), a start circuit is established for one of the cars as follows:

L1, AU2, AS, AN2, US1, L2

to energize the auxiliary start relay AS.

When the start relay AS is energized, it opens its break contacts AS1, AS2 and AS4, and closes its make contacts AS3 and AS5. The opening of the contacts AS1 interrupts the energizing circuit for the relay IS and prevents further energization of the relay IS or of the electromagnetic clutch SC until the car A has departed from the dispatching floor.

Opening of the contacts AS2 extinguishes the next lamp ANL in the car A (and the hall lantern AHL). Closure of the contacts AS3 starts the car A in any suitable manner. In the embodiment of Fig. 2, closure of the contacts AS3 illuminates the start lamp ASL which is located in the car A. This notifies the car attendant that he should start away from the dispatching floor.

Opening of the contacts AS4 deenergizes the next relay AN. Contacts AN1 reclose to permit selection of another "next" car. Contacts AN2 open, but a holding circuit around these contacts is maintained by the contacts AS5. Contacts AN3 open to prevent premature reenergization of the hall lantern and next signal.

As the car A leaves the dispatching floor, the contact 35 is moved out of engagement with the contact segment Ac. Consequently, the upper

terminal relay AU is deenergized. Contacts AU1 open to maintain the winding of the electromagnetic clutch RC deenergized until another car is at or adjacent the upper dispatching floor. Contacts AU2 open to deenergize the auxiliary start relay AS. Contacts AU3 open to decrease the possible energization of the expediter relays 2E and 3E.

The auxiliary start relay AS on being deenergized closes its contacts AS1 to permit subsequent energization of the electromagnetic clutch SC. Contacts AS2 close to prepare the next signal lamp ANL for subsequent energization, and contacts AS3 open to extinguish the starting lamp ASL. Also contacts AS4 close to prepare the relay AN for subsequent energization and contacts AS5 open.

If a dispatching interval expires before a car reaches the dispatching floor, the start relay US remains energized. As soon as a car reaches the dispatching floor, the car is promptly selected for dispatching and one of the next relay contacts AN2, BN2, CN2 or DN2 closes to energize the appropriate auxiliary start relay. Consequently, the first car to reach the dispatching floor is promptly dispatched.

In the preferred embodiment of the invention, the dispatching interval which is the sum of the intervals determined by the switch S, and the interval relays 2S and 3S is set for a heavy service demand. As long as the service demand continues, a car reaches the dispatching floor as another car leaves the dispatching floor to provide efficient system operation.

Should the service demand momentarily decrease, cars may tend to accumulate at the dispatching floor. Efficient operation under these conditions is assured by the expediter relays 2E and 3E.

The current supplied to the expediter relays 2E and 3E is dependent on the number of cars at or adjacent the dispatching floor. For example, if the car A is adjacent the dispatching floor, its brush 35 engages the contact segment Ac to energize the upper terminal relay AU. If the relay IS is energized at the same time, a circuit is established for the expediter relays as follows:

L1, AU3, AR, 51, IS3, 2E and 3E in parallel, L2

A manually operable switch 51 may be included in this circuit to render the circuit ineffective or effective as desired.

The expediter relays 2E and 3E are designed to require a certain minimum current before they can pick up. The expediter relays may be of similar construction, but the relay 3E has in series therewith a resistor ER which restricts the current through the relay 3E to a value lower than that traversing the relay 2E. The resistor AR further restricts the current supplied to both of the expediter relays.

The parameters of the circuit are so selected that the relays 2E and 3E pick up when different numbers of elevator cars are adjacent the dispatching floor. As a specific example, the relay 3E may pick up when at least three elevator cars are adjacent the dispatching floor, whereas the relay 2E picks up when only two elevator cars are adjacent the dispatching floor. It will be understood, however, that the number of elevator cars to which the relays 2E and 3E respond may be selected in accordance with the requirements of each elevator installation.

The expediter relays 2E and 3E control the effectiveness of the relays 2S and 3S in delaying

energization of the start relay US. For example, if the expediter relay 2E is energized by the presence of two cars adjacent the dispatching floor, the contacts 2E1 close. Consequently as soon as the interval relay 2S drops out, the following energizing circuit is established for the start relay:

L1, 2S2, 2E1, US, L2

Under these conditions a car is dispatched from the dispatching floor before the interval relay 3S has dropped out.

Next assume that the expediter relay 3E is energized by the presence of three elevator cars adjacent the dispatching floor. Under these circumstances the start relay US is energized through the circuit

L1, 3E1, US, L2

Therefore a car is dispatched from the dispatching floor before the interval relays 2S and 3S drop out.

If the start relay US must await the timing out of the switch S and the interval relays 2S and 3S, a long dispatching interval results. If the start relay US is energized after the switch S and the interval relay 2S have timed out, a medium dispatching interval results. Finally if the start relay US is energized after the switch S alone times out, a short dispatching interval results.

The effect of the expediter relays then is to decrease the accumulation or bunching of cars at the dispatching floor. Inasmuch as the expediter relays never dispatch two cars simultaneously, there is no tendency for the cars to bunch after leaving the dispatching floor. In this way optimum service is rendered intending passengers of the elevator system under all conditions of service demand.

Fig. 2 also shows lower terminal relays AL, BL, CL and DL which are associated with the lower terminal in the same manner by which the relays AU, BU, CU and DU are associated with the upper terminal. If desired a dispatching system may be provided for the lower terminal or lower dispatching floor which is similar to that described for the upper dispatching floor.

(A)

50 Operation of Fig. 2—No car at upper terminal

It will be assumed initially that no elevator car is at the upper dispatching floor. Under this assumed condition the system of Fig. 2 operates as follows:

55 The interval relays 2S and 3S are energized. Also the motor 39 is energized and operating. The electromagnetic clutch winding SC is energized through the circuit

L1, IS1, SC, AS1, BS1, CS1, DS1, L2

Consequently, the cam 43 is rotating for the purpose of closing the switch S.

After the expiration of a predetermined interval the cam 43 closes the switch S to complete 65 the following energizing circuit for the relay IS:

L1, IS, S, AS1, BS1, CS1, DS1, L2

The relay IS consequently opens its break contacts IS1 and IS4, and closes its make contacts 70 IS2 and IS3.

On closing, the contacts IS2 establish a holding circuit for the relay IS around the switch S. The opening of the contacts IS1 deenergizes the winding of the electromagnetic clutch SC. The contacts IS3 in closing prepare the expediter re-

lays 2E and 3E for subsequent energization. Opening of the contacts 1S4 interrupts the energizing circuit for the interval relay 2S and this relay begins to time out. It will be recalled that the relays 2S and 3S have a delayed dropout.

At this point it is assumed that the car A reaches the upper terminal or dispatching floor. As a result of the engagement of the contact segment Ac by the brush 35 of the selector, the upper terminal relay AU is energized. This relay 10 closes its make contacts AU1, AU2 and AU3. The contacts AU3 in closing complete the following energizing circuit for the expediter relays:

L1, AU3, AR, 51, 1S3, relays 2E and 3E in parallel, L2

In addition, the circuit for the expediter relay 3E includes the resistor ER. It will be recalled that the energization of the expediter relays through only one of the sets of contacts AU3 to 20 DU3 is insufficient for these relays to pick up.

In closing, the contacts AU1 establish the following energizing circuit for the winding of the electromagnetic clutch RC:

L1, AU1, RC, AN1, BN1, CN1, DN1, L2

Consequently the cam 41 starts to rotate and successively closes the switches associated therewith until the switch AY is closed. Closure of the switch AY establishes the following energizing circuit for the next relay AN:

L1, AU2, AN, AS4, AY, L2

As a result of its energization, the next relay AN opens its break contacts AN1 and closes its make contacts AN2 and AN3. Opening of the contacts AN1 interrupts the energizing circuit for the winding of the electromagnetic clutch RC and the cam 41 consequently discontinues its rotation. Closure of the contacts AN2 prepares the auxiliary start relay AS for subsequent energization. Finally closure of the contacts AN3 establishes the following energizing circuit for the next lamp and hall lantern of the car A:

L1, AN3, AS2, AHL, ANL, L2

Consequently the attendant of the elevator car A is notified promptly that his car will be the next car to leave the upper dispatching floor, and he begins loading his car.

Upon the expiration of its dropout interval, the relay 2S drops out to open its make contacts 2S1 and to close its break contacts 2S2. Opening of the contacts 2S1 interrupts the energizing circuit for the interval relay 3S, and this relay begins to time out. The delay in dropout of the interval relay 3S is determined by the resistor 49. Closure of the contacts 2S2 partially completes an energizing circuit for the start relay US. This energizing circuit is ineffective; however, unless the contacts 2E1 of the expediter relay are closed. Consequently the start relay US remains deenergized.

Upon expiration of its dropout interval, the relay 3S drops out to close its break contacts 3S1. These contacts complete an energizing circuit for the start relay US, and the start relay promptly closes its make contacts US1.

The closing of the contacts US1 completes the following energizing circuit for the auxiliary start relay AS:

L1, AU2, AS, AN2, US1, L2

The auxiliary start relay AS opens its break contacts AS1, AS2 and AS4 and closes its make contacts AS3 and AS5.

In opening, the contacts AS1 deenergize the relay 1S. This relay recloses its break contacts 1S1 and 1S4, and opens its make contacts 1S2 and 1S3. Closure of the contacts 1S1 prepares the winding of the electromagnetic relay SC for subsequent energization, but such energization cannot occur until reclosure of the contacts AS1. In opening, the contacts 1S2 terminate the holding circuit around the switch S. Opening of the contacts 1S3 prevents energization of the expediter relays 2E and 3E. Finally closure of the contacts 1S4 re-establishes the energizing circuit for the interval relay 2S.

The interval relay 2S upon energization there- 15 of closes its contacts 2S1 to re-energize the interval relay 3S and opens its break contacts 2S2 to prevent energization therethrough of the start relay US. Upon energization the interval relay 3S opens its break contacts 3S1 to prevent energization therethrough of the start relay US.

Referring again to the auxiliary start relay AS, it should be noted that upon energization this relay opens its break contacts AS2 for the purpose of extinguishing the hall lantern AHL and the next lamp ANL. Also contacts AS3 complete an energizing circuit for the start lamp ASL which notifies the car attendant that he should start from the dispatching floor. Contacts AS4 open to deenergize the next relay AN and contacts AS5 establish a holding circuit around the contacts AN2.

Since the next relay AN is deenergized, it closes the contacts AN1 to permit selection of another "next" car as promptly as possible. Also it opens the contacts AN2, but these are by-passed by the holding contacts AS5. Opening of the contacts AN3 has an immediate effect on the system.

When the car A leaves the upper dispatching floor, the brush 35 of the selector leaves the associated contact segment Ac to deenergize the upper terminal relay AU. The relay AU thereupon opens its make contacts AU1, AU2 and AU3. The opening of the contacts AU1 requires arrival of at least one other car at the upper dispatching floor before the winding of the electromagnetic clutch RC can again be energized. Opening of the contacts AU2 deenergizes the relay AS. Opening of the contacts AU3 terminates any energization of the expediter relays 2E and 3E on behalf of the car A.

Upon deenergization, the relay AS closes its contacts AS1 to permit another car to be started. Contacts AS2 and AS4 close, but have no immediate effect on system operation. Also the contacts AS3 open to extinguish the start lamp ASL, and the contacts AS5 open.

Consequently, if a car arrives at the upper dispatching floor when no other elevator car is present at such floor, the arriving car cannot be dispatched until at least a predetermined interval, which will be called a long interval, has expired, measured from the dispatch of the preceding elevator car from the upper dispatching floor. The predetermined interval is the sum of the intervals required for closure of the switch S and dropout of the relays 2S and 3S.

(B)

Car A at upper dispatching floor when subsequent car arrives

The next operation of the system illustrated in Fig. 2 to be discussed will be under the assumed conditions that the car A is at the upper dispatching floor and that car B arrives im-

mediately after the interval relay **2S** drops out. The condition of the system immediately prior to the arrival of car B at the upper dispatching floor may be ascertained by reference to the preceding discussion. When car B arrives, the relays **1S**, **AU** and **AN** are energized. The windings of the electromagnetic clutches are deenergized and the switch **S** is open. The interval relay **2S** has just dropped out to interrupt the energization of the interval relay **3S** and the interval relay **3S** now starts to time out. The expediter relays **2E** and **3E** are partially energized through the resistor **AR**, but the magnitude of the energization is insufficient for either of the expediter relays to pick up.

Upon arrival of the car B at the upper dispatching floor, the brush **B35** of its selector engages the associated contact segment **Bc** to complete an energizing circuit for the upper terminal relay **BU**. The relay **BU** closes its make contacts **BU1**, **BU2** and **BU3**. Closure of the contacts **BU1** has no immediate effect on the operation of the system for the reason that the contacts **AN1** of the next relay **AN** are open. Closure of the contacts **BU2** has no immediate effect on the operation of the system for the reason that the switch **BY** and contacts **BN2** are open.

Closure of the contacts **BU3** increases the energization of the expediter relays **2E** and **3E**. These relays now are energized through the resistors **AR** and **BR** in parallel. Such energization is insufficient to pick up the expediter relay **3E** but suffices to pick up the relay **2E**. Consequently the expediter relay **2E** picks up to close its make contacts **2E1**.

Inasmuch as the contacts **2S2** are closed as a result of the previous dropout of the interval relay **2S**, the closure of the contacts **2E1** completes a circuit for the start relay **US**. The start relay closes its make contacts **US1** to complete the following energizing circuit for the start relay **AS**:

L1, **AU2**, **AS**, **AN2**, **US1**, **L2**

Energization of the start relay **AS** starts the car A in the manner previously described.

It should be noted that the car A is started before the interval relay **3S** drops out. Consequently the car A may be said to have been dispatched upon the expiration of a medium interval measured from the dispatch of the immediately preceding car from the upper dispatching floor.

When the car A leaves the dispatching floor, the associated brush **35** leaves contact segment **Ac** to deenergize the upper terminal relay **AU**. The contacts **AU1** open but have no immediate effect upon the operation of the system. The contacts **AU2** open to deenergize the start relay **AS**. The contacts **AU3** reopen to prevent energization of the expediter relays through the resistor **AR**.

It will be recalled that the next relay **AN** is deenergized in response to energization of the relay **AS**. Upon deenergization the next relay **AN** closes its contacts **AN1** to complete an energizing circuit for the winding of the electromagnetic relay **RC** as follows:

L1, **BU1**, **RC**, **AN1**, **BN1**, **CN1**, **DN1**, **L2**

The electromagnetic clutch consequently connects the cam **41** to the motor and successively closes the associated switches until the switch **BY** is closed. Upon closure, the switch **BY** completes a circuit for the next relay **BN** as follows:

L1, **BU2**, **BN**, **BS4**, **BY**, **L2**

The next relay **BN** opens its contacts **BN1** to deenergize the winding of the electromagnetic clutch **RC** and prevent further rotation of the cam **41**. The contacts **BN2** close to prepare the auxiliary start relay **BS** for subsequent energization. The contacts **BN3** close to energize the next lamp **BNL** and the associated hall lantern. This notifies the car attendant that car B is the next car to be dispatched from the upper dispatching floor and the car attendant starts to load his car.

The opening of the contacts **AN2** and **AN3** of the next relay **AN** as a result of the energization of the auxiliary start relay **AS** has no immediate effect on the operation of the system.

When the car A received its start signal, it will be recalled that the auxiliary start relay **AS** was energized to open its contacts **AS1** thereby deenergizing the relay **1S**. The relay **1S** closed its break contacts **1S1** to prepare the winding of the electromagnetic clutch **SC** for subsequent energization. Also the contacts **1S2** opened the holding circuit around the switch **S**. The contacts **1S3** opened to deenergize the expediter relays **2E** and **3E**. The contacts **1S4** closed to energize the interval relay **2S**, and this in turn closed its make contacts **2S1** to reenergize the interval relay **3S**. The interval relays **2S** and **3S** when reenergized open their break contacts **2S2** and **3S1**.

Deenergization of the expediter relay **2E** resulted in reopening of the contacts **2E1**.

Upon departure of the car A from the upper dispatching floor and the consequent deenergization of the auxiliary start relay **AS**, the contacts **AS1** close to establish the following energizing circuit for the winding of the electromagnetic clutch **SC**:

L1, **IS1**, **SC**, **AS1**, **BS1**, **CS1**, **DS1**, **L2**

As a result of rotation of the cam **43**, the switch **S** is ultimately closed to energize the relay **1S** through the circuit:

L1, **IS**, **S**, **AS1**, **BS1**, **CS1**, **DS1**, **L2**

The relay **1S** opens its break contacts **1S1** to deenergize the winding of the electromagnetic clutch **SC** and closes its front contacts **1S2** to establish a holding circuit around the switch **S**. The spring **45** resets the cam **43** following the deenergization of the clutch winding.

The contacts **1S3** close to energize the expediter relays **2E** and **3E** through the resistor **BR**. However, such energization is insufficient to cause either of the expediter relays to pick up. The opening of the contacts **1S4** interrupts the energization of the interval relay **2S** and the interval relay starts to time out.

Upon expiration of the dropout time of the relay **2S**, the contacts **2S1** open to interrupt the energization of the interval relay **3S** and this relay promptly starts to time out. In addition the contacts **2S2** close, but have no immediate effect on the operation of the system for the reason that the contacts **2E1** are open.

Upon expiration of the dropout time of the relay **3S**, contacts **3S1** close to energize the start relay **US**. The start relay closes its contacts **US1** to complete the following circuit for the start relay **BS**:

L1, **BU2**, **BS**, **BN2**, **US1**, **L2**

The auxiliary start relay **BS** opens its break contacts **BS1** to deenergize the relay **1S**. Contacts **BS2** open to interrupt the energization of the next lamp **BNL** and the associated hall lantern. Contacts **BS3** close to illuminate the

start lamp BSL. This notifies the car attendant that he should start car B away from the upper dispatching floor. Contacts BS4 open to deenergize the next relay BN. The contacts BS5 are closed to establish a holding circuit across the contacts BN2 and US1.

The deenergization of the relay 1S results in reclosure of the contacts 1S1 and opening of the contacts 1S2. These contact changes have no immediate effect upon the operation of the system. Contacts 1S3 open to deenergize the expediter relay 2E and 3E. Contacts 1S4 close to reenergize the interval relay 2S. The interval relay 2S closes its contacts 2S1 to reenergize the interval relay 3S and open its contacts 2S2. The opening of the contacts 2S2 has no immediate effect on the operation of the system.

Energization of the interval relay 3S opens contacts 3S1 to prevent further energization of the start relay US therethrough.

The next relay BN closes its contacts BN1 to prepare the circuit of the winding of the electromagnetic clutch RC for subsequent energization. Contacts BN2 open but have no immediate effect on the operation of the system. Contacts BN3 open but have no immediate effect on the operation of the system.

As the car B leaves the upper dispatching floor, its brush B35 leaves the associated contact segment Bc. The resulting deenergization of the upper terminal relay EU results in deenergization of the auxiliary start relay BS.

The auxiliary start relay BS upon deenergization closes its contacts BS1 to complete an energizing circuit for the winding of the electromagnetic clutch SC. This starts the measurement of a new dispatching interval for the next elevator car to arrive after the dispatch of the elevator car B. The contacts BS2 close but have no immediate effect on the operation of this system. The contacts BS3 open to extinguish the start lamp BS1. The closure of the contacts BS4 and the opening of the contacts BS5 have no immediate effect on the operation of the system.

From a consideration of this phase of the operation of a system in Fig. 2 it is clear that if an elevator car, such as the car A, is present at the dispatching floor at the time a second elevator car, such as the car B, arrives, the dispatch of the car A is expedited. The car A leaves the dispatch floor upon the expiration of an interval which may be termed a medium interval. However, the long dispatching interval still must expire following the dispatch of the car A before the car B is dispatched from the dispatching floor.

It should be noted that the medium interval need not be a definite or fixed interval. The magnitude of the medium interval depends to some extent on the particular instant during the interval at which the second car B arrives at the dispatching floor. The medium interval may have a value between the time required for dropout of the relay 2S and the time required for dropout of the interval relay 3S as determined by the arrival of the car B. Consequently, if the car B arrives prior to the expiration of the dispatching interval for the car A, the dispatch of the car A is expedited.

(C)

Three cars arrive at dispatching floor simultaneously

Next it is assumed that three cars A, B and C arrive substantially simultaneously at the up-

per dispatching floor. At the time of arrival of the cars, the winding of the electromagnetic clutch SC is energized, and the cam 43 is rotating to close the switch S. The interval relays 2S and 3S are energized.

When the cars arrive at the upper dispatching floor the contact segments Ac, Bc, Cc are engaged respectively by their brushes to energize the upper terminal relays AU, BU and CU. These relays close their make contacts AU1, BU1 and CU1, AU2, BU2 and CU2, and AU3, BU3 and CU3. Closure of the contacts AU1, BU1 and CU1 completes an energizing circuit for the winding of the electromagnetic clutch RC. Consequently the motor 39 rotates the cam 41 until one of the associated switches for the cars A, B and C is closed. It will be assumed that the first of the switches to be closed is the switch AY. Closure of the switch AY completes the following circuit for the next relay AN:

L1, AU2, AN, AS4, AY, L2

The next relay AN opens its contacts AN1 to deenergize the winding of the electromagnetic clutch RC. This permits only one of the cars to be selected as the next car.

The next relay AN also closes its contacts AN2, but this has no immediate effect on the operation of the system. Closure of the contacts AN3 completes an energizing circuit for the next lamp ANL and the associated hall lantern. This notifies the car attendant that the car A has been selected as the next car to leave the dispatching floor and he starts to load his car.

The closures of the contacts AU3, BU3 and CU3 have no immediate effect on the operation of the system.

When the cam 43 closes the switch S, an energizing circuit is established for the relay 1S through the circuit:

L1, LS, S, AS1, BS1, CS1, DS1, L2

The relay 1S opens its break contacts 1S1 and 1S4, and closes its make contacts 1S2 and 1S3. The contacts 1S2 establish a holding circuit around the switch S and the opening of the contacts 1S1 prevents further energization of the winding of the electromagnetic clutch SC. The spring 45 resets the cam 43 to its starting position.

The relay 1S closes its contacts 1S3 to energize the expediter relays 2E and 3E through the resistors AR, BR and CR in parallel. These resistors supply sufficient current to pick up both of the expediter relays 2E and 3E. The expediter relay 3E closes its contacts 3E1 to complete an energizing circuit for the start relay US. The start relay closes its contacts US1 to complete the following circuit for the auxiliary start relay AS:

L1, AU2, AS, AN2, US1, L2

The auxiliary start relay AS opens its contacts AS1 to deenergize the relays 1S and AN. The contacts AS2 open to extinguish the next lamp ANL and the hall lantern for the elevator car A. In addition, the relay AS opens its contacts AS4 to deenergize the next relay AN. Contacts AS5 close to establish a holding circuit around the contacts AN2 and US1.

The contacts AS3 close to illuminate the start lamp ASL for the car A. Consequently the car attendant for the car A closes his car doors and starts his elevator car away from the dispatch-

ing floor. It should be noted that the minimum interval required under these conditions to dispatch the car A is that required for the cam 43 to close the switch S.

The deenergization of the relay 1S closes contacts 1S1 to prepare the winding of the electromagnetic clutch SC for subsequent energization. The holding contacts 1S2 are opened and the contacts 1S3 are opened to interrupt the energization of the expediter relays 2E and 3E. The contacts 1S4 close to reenergize the interval relay 2S. This reenergization takes place before the interval relay 2S has had an opportunity to drop out.

Because of its deenergization, the next relay AN closes its contacts AN1 to complete an energizing circuit for the winding of the electromagnetic clutch RC. (It will be recalled that the contacts BU1 and CU1 still are closed.) Consequently, the cam 41 is rotated by the motor 39 until either of the switches BY or CY is closed. It will be assumed that the switch BY is closed by operation of the cam 41. Closure of the switch BY completes a circuit for the next relay BN as follows:

L1, BU2, BN, BS4, BY, L2

The next relay BN opens its break contacts BN1 to deenergize the winding of the electromagnetic clutch RC. This stops rotation of the cam 41. The next relay closes its make contacts BN2, but this has no immediate effect on the operation of the system. Contacts BN3 close to energize the next lamp BNL and the associated hall lantern. This indicates to the car attendant that the car B has been selected as the next car to be dispatched from the dispatching floor. The car attendant consequently starts to load his car.

When the car A leaves the dispatching floor, the brush 35 of its selector leaves the associated contact segment Ac to deenergize the upper terminal relay AU. The resulting opening of the contacts AU1 has no immediate effect on the operation of the system. The contacts AU2 open to deenergize auxiliary start relay AS. The contacts AU3 open, but such opening has no immediate effect on the operation of the system.

The departure of car A accompanied by the closure of contacts AS1 has resulted in the energization of the winding of the electromagnetic clutch SC to effect rotation of the cam 43. Consequently the dispatcher interval for the car B is measured, from the departure of the car A, from the dispatching floor.

The cam 43 rotates until it closes the switch S to energize the relay 1S. The relay 1S closes its contacts 1S2 to establish a holding circuit around the switch S and opens its contacts 1S1 to deenergize the winding of the electromagnetic clutch SC. Contacts 1S4 open to interrupt the energization of the interval relay 2S, and this relay starts to time out.

Contacts 1S3 close to connect the expediter relays 2E and 3E for energization through the resistors BR and CR in parallel. (It will be recalled that the contacts BU3 and CU3 remain closed.) The resistors BR and CR supply sufficient current to pick up the relay 2E but do not supply sufficient current to pick up the relay 3E. The relay 2E closes its make contacts 2E1, but this has no immediate effect on the operation of the system for the reason that the contacts 2S2 are still open.

Upon expiration of the time required for the interval relay 2S to drop out, the contacts 2S1 open to interrupt the energization of the in-

terval relay 3S and this relay starts to time out. At the same time the contacts 2S2 close to complete through the contacts 2E1 an energizing circuit for the start relay US. The start relay 5 closes its contacts US1 to complete an energizing circuit for the auxiliary start relay BS as follows:

L1, BU2, BS, BN2, US1, L2

The start relay BS opens its contacts BS1 to interrupt the energization of the relay 1S. The contacts BS2 open to interrupt the energization of the next lamp BNL and the hall lantern for the car B. The contacts BS3 close to illuminate the start lamp BSL. The car attendant now is informed that he is to start from the dispatching floor. Contacts BS4 open to deenergize the next relay BN. Contacts BS5 close to establish a holding circuit around the contacts BN2 and US1.

10 It should be noted that the dispatching interval for the car B is equal to the sum of the intervals required for operation of the relays 1S and 2S. Because of the operation of the expediter relay 2E, the dropout time of the interval relay 3S is not included in the dispatching interval for the car B. Consequently the car B may be said to have a medium dispatching interval under the assumed conditions.

15 The relay 1S opens its contacts 1S2 and closes its contacts 1S1. The contacts 1S3 open to interrupt the energization of the expediter relays 2E and 3E. The contacts 1S4 close to energize the interval relay 2S. The interval relay 2S closes its make contacts 2S1 to energize the interval relay 3S. Also the contacts 2S2 are opened to prevent subsequent energization therethrough of the start relay US.

20 The next relay BN upon deenergization closes its break contacts BN1 to complete the following 40 energizing circuit for the winding of the electromagnetic clutch RC:

L1, CU1, RC, AN1, BN1, CN1, DN1, L2

(The contacts CU1 remain closed as long as the car C is at or adjacent the upper dispatching floor.)

25 The cam 41 now rotates until it closes the switch CY. This completes the following circuit for the next relay CN:

L1, CU2, CN, CS4, CY, L2

30 The next relay CN opens its contacts to interrupt the energizing circuit for the winding of the electromagnetic clutch RC. The contacts CN2 close but have no immediate effect on the operation of this system. The contacts CN3 close to illuminate the next lamp CNL and the hall lantern of the car C. The car attendant for the elevator car C now is notified that his car will be the next to leave the dispatching floor and he starts to load his car.

35 When the car B leaves the dispatching floor, the brush B35 separates from the contact segment Bc to deenergize the upper terminal relay BU. The upper terminal relay opens its contacts BU1, but this has no immediate effect on the operation of the system. Contacts BU2 open to deenergize the start relay BS. Contacts BU3 open, but such opening has no immediate effect on the operation of the system.

40 The deenergization of the auxiliary start relay closes the break contacts BS1. This completes the following circuit for the winding of the electromagnetic clutch SC:

L1, 1S1, SC, AS1, BS1, CS1, DS1, L2

As a result, the cam 43 rotates to initiate the measurement of a dispatching interval and ultimately closes the switch S to energize the relay 1S. The relay 1S closes its contacts 1S2 to establish a holding circuit around the switch S. In addition the contacts 1S1 open to deenergize the winding of the electromagnetic clutch SC. The spring 45 returns the cam 43 to its starting position. The contacts 1S3 close to complete an energizing circuit for the expediter relays 2E and 3E through the resistor CR. However, the amount of current supplied to the expediter relays is insufficient to cause pickup of either of the expediter relays.

The contacts 1S4 open to interrupt the energization of the interval relay 2S. The interval relay consequently starts to time out.

Upon the expiration of the time required for the interval relay 2S to drop out, the contacts 2S1 open to interrupt the energization of the interval relay 3S. The interval relay 3S consequently starts to time out. In addition the contacts 2S2 close, but have no immediate effect on the operation of the system for the reason that the contacts 2E1 are open.

Following expiration of time required for the interval relay 3S to drop out, the contacts 3S1 close to complete an energizing circuit for the start relay US. This relay US closes its contacts US1 to complete the following energizing circuit for the auxiliary start relay CS:

L1, CU2, CS, CN2, US1, L2

The auxiliary start relay opens its contacts CS1 to deenergize the relay 1S. The contacts CS2 open to interrupt the energization of the next lamp CNL and the hall lantern for the car C. The contacts CS3 close to illuminate the start lamp CSL. This notifies the car attendant for the car C that he should start his car away from the dispatching floor. Opening of the contacts CS4 deenergizes the next relay CN, and closing of the contacts CS5 establishes a holding circuit around the contacts CN2 and US1.

The next relay CN closes its contacts CN1 to prepare the winding of the electromagnetic clutch RC for subsequent energization. Opening of the contacts CN2 and CN3 has no immediate effect on the system.

It should be observed that the dispatching interval required for the car C is the sum of the intervals introduced by the relays 1S, 2S and 3S. Consequently, when three cars simultaneously are at the dispatching floor, the first of the cars to leave the dispatching floor is dispatched after the expiration of a short interval. The second car to leave the dispatching floor is dispatched after the expiration of a medium dispatching interval. The third car to leave the dispatching floor leaves the dispatching floor after the expiration of a long dispatching interval.

Because of the staggering in the dispatch of the cars, negligible bunching of the cars can occur either at the dispatching floor or at floors displaced from the dispatching floor. At the same time optimum service is provided for intending passengers.

The last reference to the relay 1S related to its deenergization as a result of opening of the contacts CS1. The contacts 1S2 open to interrupt the holding circuit around the switch S. The contacts 1S1 close to prepare the winding of the electromagnetic clutch SC for subsequent energization. The contacts 1S3 open to deenergize the expediter relays 2E and 3E. The contacts

1S4 close to energize the interval relay 2S. The interval relay 2S closes its contacts 2S1 to energize the interval relay 3S. Also contacts 2S2 open but have no immediate effect on the operation of the system. The interval relay 3S opens its contacts 3S1.

When the car C leaves the dispatching floor it moves the brush C35 away from the associated contact segment Cc of the car selector. The resulting deenergization of the upper terminal relay CU opens the contacts CU1. Such opening has no immediate effect on the operation of the system. Contacts CU2 open to deenergize the auxiliary start relay CS. Contacts CU3 open but have no immediate effect on the operation of the system.

Upon departure of the elevator car C and the resulting closure of the contacts CS1 of the auxiliary start relay, an energizing circuit is completed for the winding of the electromagnetic clutch SC. The cam 43 thereupon rotates to initiate the measurement of a dispatching interval for the next car to arrive at the dispatching terminal. The relay CS also closes its contacts CS2 and CS4, but such closures have no immediate effect on the system. Contacts CS3 open to extinguish the start lamp CS2. Opening of the contacts CS5 has no immediate effect on the system.

FIGURE 3

The dispatching terminals for the upper and lower dispatching floors may be independently adjustable. For example in some elevator installation the service calls may be predominantly in one direction, as in the down direction. Under these conditions the cars may be dispatched with shorter dispatching intervals from the upper dispatching floor than from the lower dispatching floor. A circuit suitable for such independent adjustment is illustrated in Fig. 3.

Each floor is provided with an up switch and a down switch which may be manually operated by intending passengers. Preferably these switches take the form of contacts on the conventional floor call registering relays employed in elevator systems.

In Fig. 3, a differentially-operated resistor 55 is adjusted through contacts of the up and down floor call registering relays. For example, each of the up-call registering relays has make contacts 1UR1 to 5UR1 connected through a separate resistor 57 to one terminal of a winding 59 of the differentially-operated resistor. In an analogous manner each of the down-call registering relays has make contacts 2DR1 to 6DR1 connected through a separate resistor 61 to one terminal of the remaining winding 63 of the differentially-operated resistor. The remaining terminals of the windings 59 and 63 are connected through a conductor 65 to the bus L1. Each of the call registering relays completes a circuit for its associated resistor 57 or 61 between the buses L1 and L2.

The windings 59 and 63 operate differentially on magnetic cores which rotate a tap 67 about an axis. The tap is biased towards a predetermined position by means of suitable springs 69. The position of the tap 67 with respect to its associated resistors 57 is determined by the difference between the service demands in the up and down directions. The adjustable resistor of Fig. 3 may be employed in place of the resistor 47 or 49 of Fig. 2, if desired, to vary the dispatching interval for one of the dispatching floors as

a function of the difference in service demand for the two directions of travel of the elevator car.

FIGURE 4

Fig. 4 shows a number of refinements which may be added to the system of Fig. 2. When the additions of Fig. 4 are employed, the switch 51 of Fig. 2 preferably is opened to remove the expeditor relays from service.

In Fig. 4 an instant dispatch relay IDU is provided for additionally controlling the dispatch of elevator cars from the upper dispatching floor. Referring to Fig. 2, it will be observed that the instant dispatch relay IDU has contacts IDU1 which are independently effective for energizing the start relay US.

The instant dispatch relay IDU may be of the inverse time-delay type. Such relays are well known in the art and have a time delay which varies as an inverse function of the magnitude of the current energizing the relay. The relay then may be energized with current having a magnitude dependent on the number of elevator cars at or adjacent the associated dispatching floor in a manner hereinafter set forth. However, it will be assumed that the instant dispatch relay IDU is of the instantaneously-operating type and that discrimination between the numbers of cars adjacent the dispatching floor is obtained by means of a resistor 72 which may be connected in parallel with the relay IDU through contacts K1 and UT1 of expeditor relays K and UT.

It will be recalled that the upper terminal relays AU, BU, CU and DU are energized respectively in response to the presence of the associated elevator cars at or adjacent the upper terminal floor. These relays have make contacts AU4, BU4, CU4 and DU4 which are effective for connecting in parallel resistors ARU, BRU, CRU and DRU through which the instant dispatch relay IDU may be energized. The parameters may be such that with the resistor 72 connected in parallel with the instant dispatch relay IDU, three of the resistors ARU, BRU, CRU and DRU must be connected in parallel for the purpose of supplying sufficient current to pick up the relay IDU. Under these conditions the presence of three or more elevator cars adjacent the upper dispatching floor supplies sufficient current to pick up the relay IDU and thereby to start instantaneously an elevator car from the associated dispatching floor. It will be observed that the instant dispatch relay is energized through break contacts US2 of the start relay US. Consequently, if the start relay has already operated to provide a start signal, the contacts US2 are open and the instant dispatch relay IDU is ineffective.

The parameters further may be so selected that if the resistor 72 is not connected in parallel with the instant dispatch relay IDU, current supplied through a pair of the resistors ARU, BRU, CRU and DRU suffices to pick up the relay IDU. Under these conditions the presence of two cars adjacent the associated dispatching floor suffices to pick up the instant dispatch relay for the purpose of starting instantaneously one of the cars from the dispatching floor.

Provision also is made for instantaneously starting an elevator car when only one car is present adjacent the dispatching floor. Such dispatching is effected by means of contacts of position relays P1, P2 and P3, and of service demand relays R0, R1, R2 and R3. Various com-

bination of these contacts are effective for bypassing the resistors ARU, BRU, CRU and DRU. When any of these combinations is present, sufficient current is passed to pick up the relay IDU promptly, regardless of the number of elevator cars adjacent the upper dispatching floor. The position and service demand relays will be discussed in greater detail below.

The connection of the resistor 72 in parallel with the relay IDU is controlled in part by the expeditor relay K. This expeditor relay K is connected for energization through various combinations of the contacts of the position and service demand relays. The expeditor relay K 15 interrupts the connection of the resistor 72 across the relay IDU when a predetermined service demand exists on the system with no elevator car in position to supply reasonably prompt service to the service demand.

20 Under some conditions it may be desirable to modify the dispatching from the upper terminal in accordance with the dispatching from the lower terminal floor. To this end, an auxiliary expeditor relay UT is provided for controlling additionally the connection of the resistor 72 across the instant dispatch relay IDU. The relay UT is controlled by contacts IDL2 of an instant dispatch relay for the lower dispatching floor. The relay UT for the upper terminal is energized 25 through the contacts IDL2 and contacts LT2 of an auxiliary relay LT for the lower dispatching floor. If the service demand for an elevator car at the lower dispatching floor results in an operation of the instant dispatch relay IDL for the lower dispatching floor, the contacts IDL2 and LT2 are closed to energize the relay UT for the upper dispatching floor. The last-named relay opens contacts UT1 which control the connection of the resistor 72 in parallel with the instant 30 dispatch relay IDU. Also a holding circuit is established for the relay UT through make contacts UT2 thereof and break contacts US3 of the start relay.

35 In order to determine the need for expedited dispatching, the service demand is ascertained for various zones of the building served by the elevator cars. Although the system is applicable to buildings having various numbers of floors, it will be assumed in Fig. 4 that the building served by the elevator cars has 17 floors. These floors are divided into zones represented by the service demand relays R0, R1, R2 and R3. The service demand R0 is associated with floors 14, 15 and 16. The service demand relay R1 is associated 40 with floors 10, 11, 12 and 13. The service demand relay R2 is associated with floors 6, 7, 8 and 9. The service demand relay R3 is associated with floors 2, 3, 4 and 5. The number of floors in each zone and the number of zones may be 45 selected in accordance with the requirements of each elevator installation.

50 Each of the floors has a switch or a call registering relay provided with contacts which may be operated by an intending passenger for controlling the energization of the associated service demand relay switch. For example, the 16th floor has contacts 16DR2 which when closed connect a resistor 16Z in series with the associated service demand relay R0. Similarly, contacts 15DR2 and 55 14DR2 control the connections of resistors 15Z and 14Z to the service demand relay R0.

60 Each service demand relay may be designed to pick up when any predetermined service demand is reached for the associated zone. For example, 65 it will be assumed that each of the service de-

mand relays picks up when energized by current flowing through at least two of the resistors associated therewith. It will be understood that each of the down floor call registering relays closes its contacts in response to actuation of a floor button for the associated floor. The contacts remain closed until the floor call is answered.

The position of the elevator cars may be ascertained in any suitable manner. For example, the selector for the car A is provided with a row of contact segment A_f which are engaged successively by brushes 81 and 82 as the car moves from floor to floor. The contact segments in Fig. 4 are labeled A_f6 to A_f16 . By inspection of Fig. 4, it will be noted that the position relay P_1 is energized when any of the segments A_f14 , A_f15 or A_f16 engages one of the brushes 81 or 82. A circuit for the position relay is completed through contacts A_{X1} of a direction switch which are closed when the car is conditioned for movement in a down direction. Such direction switches may be manually operated but preferably are automatically operated in a manner well known to the art. In an analogous manner the position relay P_2 is energized when any of the associated contact segments A_f10 to A_f13 is engaged by one of the brushes 81 or 82. The position relay P_3 is energized when any of the contact segments A_f6 to A_f9 is engaged by one of the brushes 81 or 82, and the car is set for down travel. The brushes may be arranged to contact each segment before contact is broken with the immediately preceding segment.

It will be understood that a row of segments similar to the segments A_f6 to A_f16 is provided for each of the elevator car selectors. The arrows in Fig. 4 are to be connected to corresponding segments for the remaining elevator cars B, C and D. Each of the cars also would have brushes similar to the brushes 81 and 82 for engaging the associated contact segments. Consequently, when the position relay P_1 is picked up it indicates that at least one of the elevator cars A, B, C or D is positioned in the zone including floors 14, 15 and 16, and is set for travel in the down direction. The position relay P_2 conveys similar information for cars positioned in the next lower zone. Similarly the position relay P_3 when picked up indicates that a car set for down travel is positioned in the associated zone.

It will be noted that the service demand relays R_0 to R_2 are connected to their associated resistors through appropriate contacts on the position and service demand relays. Thus the service demand relay R_0 cannot be energized if one or more cars set for down travel is positioned in the associated zone. This is true for the reason that the service demand relay R_0 must be energized through the break contacts P_1-3 of the position relay P_1 . Consequently, if the contacts P_1-3 are open signifying the presence of a car set for down travel in the associated zone, the service demand relay R_0 cannot be energized.

Similarly, if elevator cars are set for down travel in the zones of position relays P_1 and P_2 (contacts P_1-4 and P_2-4 are open), the service demand relay R_1 can not be energized. If elevator cars positioned in the zone represented by floors 6 to 9 and in either of the higher zones (contacts P_3-5 and either P_1-5 or P_2-5 are open), the service demand relay R_2 cannot be energized.

If a down-traveling car is in the zone of the position relay P_2 , the service demand relay R_1 can still be energized through either of two cir-

cuits. If no car is in the zone of position relay P_1 , and if a service demand exists for the lower zone represented by the service demand relay R_2 , the service demand relay R_1 can be energized through the contacts R_2-7 and P_1-4 . If no cars are in the zones represented by the position relays P_1 and P_3 , and if a service demand exists for the lower zone represented by relay R_3 , the relay R_1 can be energized through the contacts R_3-5 , P_3-4 and P_1-4 .

If no cars set for down travel are positioned in the zones represented by the relays P_1 and P_2 and if a service demand exists in the zone represented by the service demand relay R_3 , the service demand R_2 can be energized through the contacts R_3-6 , P_1-5 and P_2-5 .

Preliminary operation Figure 4

It is believed desirable at this stage to discuss briefly a typical operation of the portion of the system of Fig. 4 thus far specifically described. The purpose of the position and service demand relays is to expedite the dispatch of a car from the upper terminal in the event that a service demand exists in a zone with no car positioned to answer the service demand with reasonable promptness. (A similar system may be employed for dispatching from the lower dispatching floor if so desired. For present purposes, it will be assumed that the service demand of building is predominantly in a down direction.)

The system further contemplates additionally expediting the dispatching of elevator cars in the event that service demands exists in two zones with no car in position to provide reasonably prompt service therefor.

Referring first to the relay K , it will be observed that an energizing circuit for the relay is completed through the break contacts R_1-4 , R_2-3 and R_3-3 of the service demand relays. Consequently, the relay K normally is in energized or picked-up condition. As long as the relay K remains energized and the cars remain properly distributed, the cars will arrive at the upper dispatching floor and will be dispatched at intervals substantially equal to the sum of the intervals required for closure of the switch S and the dropout of the relays $2S$ and $3S$ of Fig. 2. Should three or more elevator cars accumulate at or adjacent the upper dispatching floor, sufficient current is supplied through three sets of the contacts AU_4 to DU_4 to the instant dispatch relay IDU to dispatch one of the cars immediately from the terminal.

Should a service demand on the system occur which results in dropout of the relay K , the contacts K_1 open to interrupt the connection of the resistor 72 in parallel with the relay IDU . Under these conditions, the presence of only two elevator cars at or adjacent the upper dispatching floor results in immediate dispatch of one elevator car. The conditions under which the relay K drops out now will be considered.

It will be recalled that the relay K normally is picked up. Should a service demand result in the picking up of the relay R_3 to open the contacts R_3-3 , the relay K drops out to expedite the dispatch of cars from the upper terminal. However, if under the same circumstances a car is positioned above the zone of the service demand relay R_3 , the relay K does not drop out. For example, if a car conditioned for down travel were positioned in the zone of the position relay P_3 , contacts P_3-3 would be closed to establish a shunt around the contacts R_3-3 . Consequently, the relay K would not drop out.

As a further example, if a car were positioned in the zone represented by the position relay **P2** and were conditioned for down travel, contacts **P2-3** would be closed to maintain the energization of the relay **K** through the circuit

L1, K, R1-4, P2-3, R2-4, L2

If a car were in the zone represented by the position relay **P1** and conditioned for down travel, the relay **K** would be maintained energized through the circuit

L1, K, P1-2, R2-5 or R1-5, R1-6, R2-6, L2

In an analogous manner, it will be found that if any of the service demand relays **R0**, **R1** or **R2** is picked up with no down traveling car positioned in a zone above the picked-up service demand relay, the relay **K** will drop out to expedite the dispatching of an elevator car from the upper dispatching floor.

As a further example, it will be assumed that a service demand results in the pickup of the relay **R2** (contacts **R2-3**, **R2-4**, **R2-5**, **R2-6** are open). If no cars are conditioned for down travel in the zones represented by the position relays **P1** or **P2** (contacts **P1-2** and **P2-3** are open), the relay **K** drops out. If a car is positioned in the zone represented by the position relay **P1** and is conditioned for down travel, the contacts **P1-2** are closed, and the relay **K** is maintained in picked-up condition through the circuit

L1, K, P1-2, R1-5, R3-5, L2

If service demands exist in two or more of the zones at the same time with no car in position to answer the service demands with reasonable promptness, the instant dispatch relay **IDU** is energized. If a single car is present at the upper terminal, the car is dispatched instantly by such energization of the relay **IDU**. If no car is present at the upper terminal, the first car to reach the upper terminal is instantly dispatched. The energization of the relay **IDU** under these conditions is effected by connecting the relay directly across the buses **L1**, **L2** through suitable contacts of the position and service demand relays.

For example, let it be assumed that no car is positioned in any of the zones represented by the position relays **P1**, **P2** and **P3**. Under these circumstances, the break contacts **P1-1**, **P2-1** and **P3-1** are closed. If service demands exist in the zone represented by the service demand relay **R3** and the zone represented by either of the service demand relays **R0** or **R1**, the make contacts **R3-1** and **R0-1** or **R1-1** are closed. Thus a circuit is completed for energizing and picking up the relay **IDU** as follows:

L1, P1-1, P2-1, P3-1, R3-1, R1-1 or R0-1, US2, IDU, L2

The pick-up relay **IDU** dispatches a car from the upper terminal as promptly as possible.

Again let it be assumed that no car is positioned in either of the zones represented by the position relays **P1** and **P2** (break contacts **P1-1** and **P2-1** are closed). Let it be assumed further that service demands exist in the zones represented by the service demand relays **R2** and either **R0** or **R1** (make contacts **R2-1** and **R1-2** or **R0-2** are closed). Under these conditions an energizing circuit is established for the instant dispatch relay **IDU** as follows:

L1, P1-1, P2-1, R2-1, R0-2 or R1-2, US2, IDU, L2

Again a car is dispatched as promptly as possible from the upper terminal.

If no car is present in the zone represented by the position relay **P1** and service demands exist in the zones represented by the service demand relays **R1** and **R0** (make contacts **R1-3** and **R0-3** are closed), a circuit is established for the instant dispatch relay **IDU** as follows:

L1, P1-1, R1-3, R0-3, US2, IDU, L2

As a final example, if no car is positioned in either of the zones represented by the position relays **P2** and **P3** (break contacts **P2-2** and **P3-2** are closed) and service demands exist in the zones represented by the position relays **R2** and **R3** (make contacts **R3-2** and **R2-2** are closed), the following energizing circuit is established for the instant dispatch relay **IDU**:

L1, P2-2, P3-2, R3-2, R2-2, US2, IDU, L2

It will be understood that when these circuits are established the full voltage across the buses **L1** and **L2** is applied across the relay **IDU**.

When the relay **IDU** is energized, its contacts **IDU1** (Fig. 2) close to energize the start relay **US**. The start relay dispatches a car as set forth in the discussion of Fig. 2.

If similar service demands exist for up floor calls, a dispatcher may be provided for the lower dispatching floor which is similar to that described for the upper dispatching floor. For the purpose of discussion, however, it will be assumed that the service demands are present only for calls in the down direction. Under these conditions when the dispatch of a car from the upper terminal is expedited, the dispatch of a car from the lower dispatching floor similarly may be expedited.

The dispatcher for the lower dispatching floor includes a start relay **LS** and relay contacts **3SL1** which correspond respectively to the start relay **US** and contacts **3S1** associated with the dispatcher for the upper dispatching floor. It will be understood that when a car leaves the lower dispatching floor a timer similar to that including the switch **S** and the relays **2S** and **3S** of Fig. 2 measures a dispatching interval and finally closes the contacts **3SL1** to energize the start relay **LS**. The relay **LS** operates in a manner similar to that of the relay **US** for the upper dispatching floor to start the next car from the lower dispatching floor. Contacts **3EL1**, **2SL2** and **2EL1** of Fig. 4 correspond to the contacts **3E1**, **2S2** and **2F1** of Fig. 2.

In order to expedite the dispatch of elevator cars from the lower dispatching floor, the instant dispatch relay **IDL** is provided and this relay corresponds to the relay **IDU** provided for the upper dispatching floor. The relay **IDL** may be energized through resistors **ARL**, **BRL**, **CRL** and **DRL** which correspond to the resistors **ARU** to **BRU** provided for the dispatcher associated with the upper dispatching floor. Connections of the resistors **ARL** to **DRL** to the instant dispatch relay **IDL** are controlled by contacts **AL4** to **DL4** of the lower terminal relays **AL** to **DL**.

A resistor **73** is provided which may be connected in parallel with the winding of the relay **IDL** through relay contacts **T1** and **LT1**. The resistor **73** corresponds to the resistor **72**. When it is connected in parallel with the winding of the relay **IDL**, the resistor **73** may require the presence of three or more cars at or adjacent the lower dispatching floor before suf-

ficient current is supplied to pick up the relay IDL. If ether of the contacts T1 or LT1 are open, the parameters may be such that the presence of two cars at or adjacent the lower dispatching floor suffices to pick up the relay IDL.

When the dispatch of an elevator car from the upper dispatching floor is expedited, it may be desirable to expedite similarly the dispatch of an elevator car from the lower dispatching floor. Such expedition may be effected by the relay T which is controlled by contacts K2 and IDU2. When the relay K drops out to expedite the dispatch of a car from the upper dispatching floor, it opens its make contacts K1 and closes its break contacts K2. The upper dispatching floor relay IDU picks up when two cars are at or adjacent the upper dispatching floor and closes its makes contact IDU2. This completes an energizing circuit for the relay T. The relay T establishes a holding circuit through its make contacts T2 and break contacts LS3 of the start relay LS for the lower dispatching floor. The relay T also opens its break contacts T1 to interrupt the parallel connection of the resistor 73 across the relay IDL. The relay IDL now can pick up when only two cars are at or adjacent the lower dispatching floor. When a car thereafter is dispatched from the lower terminal, the contacts LS3 of the lower terminal start relay open to reset the relay T.

It may be desirable to expedite the dispatch of an elevator car when a predetermined service demand is registered by the car buttons within the elevator car. For example, let it be assumed that the elevator car A has been selected as the next car to leave the lower dispatching floor (contacts ANL4 of a next relay for the dispatcher for the lower dispatching floor are closed. Such a next relay corresponds to the next relay AN for the upper dispatching floor.) Let it be assumed further that the car A is set for up travel (contact AW1 of an up preference switch are closed. The contacts may be manually closed but ordinarily are automatically operated in a manner well understood in the art when the car A is conditioned for upward travel.)

The car A is provided with car call buttons which may be actuated to stop the elevator car at any of the floors served thereby. For each car button actuated, one of the sets of contacts 2CR1 to 16CR1 is closed. The contacts may be manually operated from within the car A. The operation of such car buttons is well understood in the art.

Each of the sets of contacts 2CR1 to 16CR1 controls the connection of an associated resistor 2Y to 16Y in circuit with a service demand relay ACC. When a predetermined number of the resistors are connected in parallel, by operation of their associated contacts 2CR1 to 16CR1, the relay ACC is energized sufficiently to pick up. For example, the service demand relay ACC may be designed to pick up in response to the connection therethrough of five or more of the resistors 2Y to 16Y. When it picks up the relay ACC closes its contacts ACC1. If the car is at the lower dispatching floor, the make contacts AL5 of the lower terminal relay are closed and a circuit is completed for the relay LT. This relay when energized opens its break contacts LT1 to interrupt the connection of the resistor 73 across the relay IDL. Consequently, the relay IDL picks up in re-

sponse to the presence of only two cars adjacent the lower dispatching floor. It will be understood that each of the remaining elevator cars is provided with a relay BCC, CCC or DCC which is energized in response to operation of a predetermined number of the associated car buttons in a manner analogous to the operation of the relay ACC for the car A. Each of the relays has make contacts which control in part the energization of the relay LT. Contacts AL5 to DL5 are associated with the contacts ACC1 to DCC1, respectively, in the manner clearly shown in Fig. 4.

When one of the relays ACC to DCC operates to expedite the dispatch of an elevator car from the lower dispatching floor, it may be desirable to expedite simultaneously the dispatch of an elevator car from the upper dispatching floor. This is effected by a relay UT which has break contacts UT1 positioned to interrupt the connection of the resistor 72 across the relay IDU. Such interruption of the connection of the resistor 72 expedites the dispatch of a car from the upper dispatching floor in a manner which will be apparent from the preceding discussion.

When the relay LT is picked up to expedite the dispatch of an elevator car from the lower dispatching floor, make contacts LT2 are closed to prepare the relay UT for energization. When the instant dispatch relay IDL for the lower dispatching floor picks up, make contacts IDL2 close to complete an energizing circuit for the relay UT. A holding circuit for the relay UT is established through the make contacts UT2 and break contacts US3 of the start relay for the upper dispatching floor. When the relay US thereafter operates to dispatch a car from the upper terminal floor, the contacts US3 open to deenergize the relay UT.

If desired, relays similar to the relays ACC to DCC and LT may be provided for expediting the dispatch elevator cars from the upper dispatching floor in response to the car call service demand. However, in most elevator installations, such relays are not required for the upper dispatching floor.

Operation of Figure 4

It is believed advisable at this stage to review briefly a typical operation of the system including components shown in Fig. 4.

Let it be assumed that the car A arrives at the upper dispatching floor. This car is selected as the next car to leave the dispatching floor by energization of the next relay AN in the manner discussed with reference to Fig. 2. Also the dispatcher for the upper dispatching floor measures a dispatching interval for the car A by operation of the interval relays 1S, 2S and 3S, in a manner which will be clear from the discussion of the operation of Fig. 2. It will be assumed that the switch 51 of Fig. 2 is open. It will also be understood that the car A on arriving at the upper dispatching floor establishes an energizing circuit for its upper terminal relay AU.

Referring to Fig. 4, it will be noted that contacts AU4 close on arrival of the elevator car adjacent the upper dispatching floor, but the resulting energization of the instant dispatch relay IDU is insufficient to pick up the relay.

Let it be assumed next that a down floor call is registered at the 10th floor. As a result of such registration, the down floor call registering relay for the 10th floor picks up and closes its make contacts 10DR2. However, the resulting ener-

gization of the service demand relay R_1 is insufficient to pick up this relay.

It will be assumed next that the car B arrives at the upper dispatching floor. Such arrival results in energization of the upper terminal relay BU . This relay closes its contacts $BU4$, but the resulting energization of the instant dispatch relay IDU still is insufficient to pick up the relay. (It will be understood that the contacts $K1$ and $UT1$ are closed to connect the resistor 72 across the relay IDU .)

At this stage a down floor call is registered at the 11th floor. The resulting closure of the make contacts $11DR2$ connects the resistors $11Z$ and $10Z$ in parallel for the purpose of energizing the service demand relay $R1$. It is assumed that no car is in the zone represented by the position relay $P2$ and sufficient current now is supplied to the service demand relay $R1$ to pick up this relay. The relay $R1$ closes its make contacts $R1-1$, $R1-2$, $R1-3$ and opens its break contacts $R1-4$, $R1-5$ and $R1-6$.

Closure of the contacts $R1-1$, $R1-2$ and $R1-3$ has no immediate effect on the operation of the system for the reason that contacts $R3-1$, $R2-1$ and $R9-3$, respectively, are open.

However, the contacts $R1-4$ in opening de-energize the relay K and this relay drops out to open its make contacts $K1$ and close its break contacts $K2$. The opening of the contacts $K1$ interrupts the connection of the resistor 72 across the relay IDU and this relay now is energized sufficiently by the presence of two cars at or adjacent to the upper terminal to pick up. The relay IDU in picking up closes its make contacts $IDU1$ and $IDU2$. The contacts $IDU1$ (Fig. 2) complete an energizing circuit for the start relay US and this relay operates to start the car A in the manner discussed with reference to Fig. 2.

The closures of the contacts $IDU2$ and $K2$ complete a circuit for the relay T . The relay T in turn completes a holding circuit through the contacts $T2$ and $LS3$. In addition, the energization of the relay T opens contacts $T1$ to interrupt the connection of the resistor 73 across the relay IDL . The relay IDL now can be energized by the presence of two elevator cars at or adjacent to the lower dispatching floor. Consequently in expediting the dispatch of a car from the upper dispatching floor, provision is made simultaneously for expediting the dispatching of an elevator car from the lower dispatching floor.

When the car A leaves the upper dispatching floor, contacts $AU4$ of the upper terminal relay AU reopen. The energization of the relay IDU is no longer sufficient to maintain the relay picked up even though the contacts $US2$ reclose, and this relay consequently now has open contacts $IDU1$ and $IDU2$. However, the relay K remains dropped out until the car A has answered the down call from the 11th floor. When this call is answered, the contacts $11DR2$ open and the energization of the relay $R1$ no longer is sufficient to maintain the relay picked up. Consequently, contacts $R1-4$ reclose to energize the relay K . This relay recloses its contacts $K1$ to reconnect the resistor 61 across the relay IDU . Contacts $K2$ open but have no immediate effect on the operation of the system. Since the contacts $T1$ are open, arrival or presence of two cars at or adjacent the lower terminal floor results in energization of the relay IDL and dispatch of a car from the lower terminal floor. The sequence for dispatching the car following

energization of the relay IDL will be understood from the explanation of the dispatch of a car from the upper terminal floor in response to energization of the corresponding relay IDU . 5 When the start relay LS is energized to dispatch the car from the lower terminal floor, the contacts $LS3$ open to deenergize or reset the relay T .

It will be assumed next that the cars A and B are at the upper terminal floor when down floor calls are registered at the 10th and 11th floors, and that the car C is in the zone represented by the position relay $P1$ and is conditioned for travel in the down direction. Under 15 such circumstances, the relay $P1$ would be picked up and the make contacts $P1-2$ would be closed. Because of the closure of the contacts $P1-2$, energization of the relay K is maintained despite the opening of the contacts $R1-4$. The alternate energizing circuit for the relay K may be traced as follows:

$L1, K, P1-2, R2-5, R3-5, L-2$

Consequently, the resistor 72 would remain connected across the relay IDU and the car A would be dispatched upon the expiration of its regular dispatching interval. In the meantime the car C in travelling downwardly would pick up the floor calls on the 11th and 10th floors to de-30 energize the service demand relay $R1$.

In the preceding discussion, reference was made to the floor call registering relays. Although such relays are well known in the art, it is believed desirable to show a typical circuit 35 therefor. Referring to Fig. 5, a floor push button $6D$ is assumed to be located at the 6th floor. When actuated, this push button completes a circuit for a floor call registering relay $6DR$. The registering relay establishes a holding circuit 40 around the push button $6D$ through contacts $6DR3$.

It will be understood that the selector for each of the elevator cars has a row of contact segments (Ag for the car A) which are engaged 45 successively by a brush (84 for the car A) as the associated elevator car moves past the floors served thereby. The contact segment for each of the floors is energized throughout the contacts of the associated floor call registering relay. 50 Thus the contact segment $6Ag$ is connected to the bus $L1$ through the contacts $6DR3$. The bus also is connected through the contacts $6DR3$ to similar contact segments for the other elevator cars of the bank by means of a connection 83.

Each of the elevator cars has a stopping relay 55 connected between the associated brush 84 and the bus $L2$ through contacts of a down preference switch. Thus the car A has a stopping relay AST which is connected between the brush 84 and the bus $L2$ through contacts $AX2$ of a down preference switch. The contacts $AX2$ are closed when the car is conditioned for down travel. They may be closed manually, but ordinarily they are closed automatically in a manner well understood in the art. When the brush 84 during down travel of the car A reaches the contact segment $6Ag$ which is connected to the bus $L1$, the relay AST is energized to stop the elevator car at the 6th floor. The mechanism for so stopping the 65 elevator car is well understood in the art.

Each of the selectors for the elevator cars is provided with a row of contact segments for cancelling the floor calls. For example, the car A has a row of contact segments Ah which are 70 engaged successively by a brush 86 as the car

moves past the floors served thereby. Each of the contact segments is connected through an associated cancellation coil and make contacts of the floor call registering relay to the bus L1. Thus the contact segment 6Ah is connected through the cancellation coil 6ER and the contacts 6DR3 to the bus L1. The cancellation coil 6ER is wound oppositely to the winding of the relay 6DR. Consequently when the cancellation coil is energized, it neutralizes the force exerted by the winding of the relay 6DR on the contacts 6DR3 and the contacts consequently re-open. The coil 6ER is connected to cancellation contact segments associated with the other elevator cars through a connection 85.

The brush 86 is connected to the bus L2 through contacts AX3 of the down preference switch. As the car A answers the floor call at the 6th floor, the brush 86 engages the contact segments 6Ah to energize the cancellation coil 6ER. This cancels the floor call for the 6th floor.

Although the invention has been described with reference to certain specific embodiments thereof, numerous modifications falling within the spirit and scope of the invention are possible.

I claim as my invention:

1. An elevator dispatching system for a plurality of elevator cars serving a plurality of floors, comprising a non-rotational dispatcher for dispatching the elevator cars from one of the floors, said dispatcher comprising a selecting device for selecting successively each car to be dispatched from the dispatching floor, a timer for determining a first timing interval for starting successive cars from the dispatching floor, and secondary timing mechanism responsive to the presence of a predetermined first number of cars at the dispatching floor for changing the timing interval for starting two successive cars to two intervals which differ from each other.

2. An elevator dispatching system for a plurality of elevator cars serving a plurality of floors, comprising a dispatcher for dispatching the elevator cars from one of the floors, said dispatcher comprising a selecting device for selecting successively each car to be dispatched from the dispatching floor, a timer for determining a first timing interval for starting successive cars from the dispatching floor, and secondary timing mechanism responsive to the presence of a predetermined first number of cars at the dispatching floor for changing the timing interval to a second value, said secondary timing means comprising an adjuster responsive to the presence of a second predetermined number of cars at the dispatching floor for changing the timing interval to a third value.

3. An elevator dispatching system for a plurality of elevator cars serving a plurality of floors, comprising a non-rotational dispatcher for dispatching the elevator cars from one of the floors, said dispatcher comprising a selecting device for selecting successively each car to be dispatched from the dispatching floor, a timer for determining a first timing interval for starting successive cars from the dispatching floor, and secondary timing mechanism responsive to the presence of a predetermined first number of cars at the dispatching floor for changing the timing interval, a next device for each of the elevator cars, actuation means responsive to the selecting device for actuating the next device for the car selected to leave the dispatching floor, a start device for each of the cars and operating means effective only after actuation of the next device

and after expiration of the timing interval for each of the elevator cars for operating the start device of the car having an actuated next device.

4. An elevator dispatching system for a plurality of elevator cars serving a plurality of floors, comprising a dispatcher for dispatching the elevator cars from one of the floors, said dispatcher comprising a first timer and a second timer for delaying dispatch of a car, selective means effective only after successive operations of the first and second timers for dispatching the next car to be dispatched from the dispatching floor, and an expediter responsive to the presence of a predetermined number of cars adjacent the dispatching floor for rendering the second timer ineffective for delaying dispatch of a car to be dispatched from the dispatching floor.

5. A system as claimed in claim 4 wherein the expediter is responsive to a second predetermined number of cars adjacent the dispatching floor for rendering both of the timers ineffective for delaying dispatch of the next car to be dispatched.

6. An elevator dispatching system for a plurality of elevator cars serving a plurality of floors, comprising a non-rotational dispatcher for dispatching the elevator cars from one of the floors, said dispatcher comprising a non-rotational selecting device effective for selecting following their arrival at the dispatching floor cars to be dispatched from the dispatching floor, timing means effective for establishing a dispatching interval between successive cars to be dispatched from the dispatching floor, said dispatching interval comprising the sum of a plurality of time increments, and an expediter responsive to the number of cars adjacent the dispatching floor for decreasing the number of said increments in a dispatching interval.

7. A system as claimed in claim 6 wherein each of the time increments is established by a separate timing relay, and the expediter operates in response to the number of cars adjacent the dispatching floor to render ineffective certain of the timing relays.

8. A system as defined in claim 6 in combination with a signal for each of the cars, connections between the selecting device and the signals effective upon selection of a car to be dispatched for promptly operating the signal for the selected car to indicate that the selected car will be the next car to leave the dispatching floor, and means responsive to expiration of the dispatching interval for the selected car to dispatch the selected car from the dispatching floor.

9. A system as defined in claim 6 wherein said time intervals may be employed for defining a short dispatching interval, a medium dispatching interval and a long dispatching interval, said dispatcher when a single car is present at the dispatching floor being effective for dispatching said car upon expiration of said long dispatching interval, said expediter being effective in response to the presence of a plurality of cars at the dispatching floor for establishing the medium interval for the first car to be dispatched, and for establishing the long dispatching interval for the second car to be dispatched, and said expediter being effective in response to a number of cars, larger than the plurality, at the dispatching floor for establishing the short interval for a first car to be dispatched from the dispatching floor, for establishing the medium interval for a second car to be dispatched from the dispatching floor and for establishing the long interval for a third car to be dispatched from the dispatching floor.

10. In a dispatcher for an elevator system having cars to be dispatched from a dispatching floor, a dispatching relay, connections including a first timer relay and a second timer relay independently effective when operated for controlling the energization of the dispatching relay, an expeditor including a relay normally rendering the first timer relay ineffective for controlling the energization of the dispatching relay independently of the second timer relay, and connections responsive to a number of cars in excess of one at the dispatching floor for operating the expeditor relay to render effective the first timer relay for controlling the energization of the dispatching relay.

11. A dispatcher as claimed in claim 10 wherein the expeditor includes a second relay for controlling the energization of the dispatching relay independently of the timer relays, and connections responsive to the number of cars at the dispatching floor for controlling the operation of the second relay, said last-named number being larger than the first-named number.

12. A dispatcher as claimed in claim 10 in combination with a third timer relay for initiating a timing operation, said timer relays being interlocked for operation in a predetermined sequence initiated by the third timer relay.

13. A dispatcher as claimed in claim 12 in combination with means responsive to each dispatch of an elevator car from the dispatching floor for resetting the timing relays.

14. In an elevator system having a plurality of cars serving a plurality of floors, a dispatcher for dispatching the elevator cars successively from a dispatching floor, said dispatcher comprising a selector for selecting a car to be dispatched, call demand means responsive to service calls from floors served by the cars, position means responsive to the positions of the cars, and an expeditor responsive to the demand means and the position means for expediting to a predetermined extent the dispatch of a car from the dispatching floor when no car is in position to serve a predetermined demand, said floors being divided into a plurality of successive zones each containing a plurality of floors, the demand means comprising a plurality of demand units each responsive to the service demand from a separate one of the zones, and the position means comprising a plurality of position units each responsive to the presence of any of the cars in a separate one of the zones.

15. A system as claimed in claim 14 wherein said expeditor is responsive to a predetermined service demand from a first one of the zones with no previously dispatched car positioned to serve the zone and to the presence of at least a predetermined number of cars adjacent the dispatching floors for expediting the dispatch of a car from the dispatching floor, and wherein the expeditor is effective in response to predetermined service demands from a plurality of said zones for expediting the dispatch of a car from the dispatching floor when less than said predetermined number of cars are adjacent the dispatching floor.

16. In an elevator system having a plurality of elevator cars for serving successive vertical zones of a building, each zone containing a plurality of floors, a dispatcher for dispatching the elevator cars successively from a dispatching floor, said dispatcher comprising a selector for selecting a car to be dispatched, separate call demand means responsive to the service demand for each of the zones, separate position means

responsive to the presence of an elevator car in each of the zones, connections for certain of the call demand means for controlling the energization of certain of the call demand means in accordance with the conditions of the position means and of other of the call demand means, the connections rendering one of said certain of the call demand means non-responsive to service demand if a car is positioned in the associated zone unless a service demand also exists

5 for a lower zone with no car positioned above said associated zone, an expeditor for expediting the dispatch of a car from the dispatching floor, connections for energizing the expeditor in accordance with the conditions of the call demand means and the position means, said connections being effective for operating the expeditor to expedite dispatching if a predetermined service demand exists in the zones with no previously-dispatched car in position to answer the service demand.

10 17. A system as set forth in claim 16 wherein said connections are also effective for operating the expeditor to still further expedite dispatching if a second predetermined service demand greater than said first predetermined service demand exists.

15 18. A system as set forth in claim 17 wherein the expeditor in response to the first predetermined service demand expedites dispatching of a car in the presence of at least a predetermined number of cars adjacent the dispatching floor and in response to the second predetermined service demand expedites dispatching of a car 20 should less than said predetermined number of cars be adjacent the dispatching floor.

25 19. An elevator dispatching system for a plurality of elevator cars serving two terminal floors and a plurality of floors intermediate the terminal floors, comprising a first dispatcher for dispatching the elevator cars at intervals from a first one of the terminal floors, a second dispatcher for dispatching the elevator cars at intervals from a second one of the terminal floors, 30 controller means responsive to a change in traffic conditions of the elevator system for changing the interval of the first dispatchers, and means responsive to an operation of the controller means for changing the interval of the second dispatcher.

35 20. An elevator dispatching system for a plurality of elevator cars serving two terminal floors and a plurality of floors intermediate the terminal floors, comprising a first dispatcher for dispatching the elevator cars at intervals from a first one of the terminal floors, a second dispatcher for dispatching the elevator cars at intervals from a second one of the terminal floors, controller means responsive to a temporary 40 change in service demand for temporarily changing the interval of the first dispatcher, and means responsive to a change in the interval of the first dispatcher for similarly changing the interval of the second dispatcher.

45 21. A dispatching system for a plurality of elevator cars serving a pair of terminal floors and a plurality of floors intermediate the terminal floors, each of the elevator cars having car call means for indicating floor stops desired by car passengers, comprising a dispatcher for dispatching the cars from a first one of the terminal floors, means for selecting a car to be dispatched from the first one of the terminal floors, and means responsive to a predetermined service 50 demand from the car call means of a car selected

35

for dispatching for expediting the dispatch of the car from the first one of the terminal floors.

22. A dispatching system as claimed in claim 21 in combination with means responsive to a predetermined service demand from the floors for expediting dispatch of a car selected for dispatching.

23. A dispatching system as claimed in claim 22 in combination with means responsive to the accumulation of a predetermined number of cars adjacent a dispatching floor for expediting the dispatch of a car selected for dispatching.

24. In an elevator system having a plurality of cars serving a plurality of floors, a dispatcher for dispatching the elevator cars successively from a dispatching floor, said dispatcher comprising a selector for selecting a car to be dispatched, call demand means responsive to service calls from floors served by the cars, position means responsive to the positions of the cars, and an expeditor responsive to the demand means and the position means for expediting to a predetermined extent the dispatch of a car from the dispatching floor when no car is in position to serve a predetermined demand, said expeditor in response to a demand greater than said predetermined demand by a predetermined amount when insufficient previously dispatched cars are positioned to serve the demand expediting to an extent greater than said predetermined extent the dispatch of a car from the dispatching floor.

25. In a dispatching and scheduling system for a plurality of elevator cars serving a plurality of floors and a dispatching floor; a starting device for each of said cars; mechanism adapted upon each operation to actuate one of said starting devices; means for causing said mechanism normally to operate at timed intervals; means for causing the starting device actuated in response to each operation of said mechanism to be for a car positioned at said dispatching floor; call mechanism for each of a plurality of intermediate floors served by the elevator cars for registering a call for service; and means responsive to a

36

predetermined number of calls for service being registered from only a predetermined group of the intermediate floors for expediting an actuation of one of said starting devices for a car at said dispatching floor.

26. In an elevator system having cars operable in two directions to serve a plurality of floors of a structure, a dispatcher having an adjustable timing schedule for successively dispatching elevator cars at intervals from a dispatching floor, call mechanism for each of the floors for registering calls for elevator service in each of said directions of travel, differential mechanism responsive to calls registered by the call mechanism for ascertaining the difference in elevator service demand for the two directions of travel, and adjusting mechanism controlled by the differential mechanism in accordance with said difference for adjusting said timing schedule as a function of said difference.

27. In an elevator system having a plurality of elevator cars for serving a plurality of floors and a dispatching floor, a dispatcher device for each of the elevator cars designed for operation when the associated elevator car is to leave the dispatching floor, a dispatcher effective at timed intervals for operating one of said dispatcher devices in order to dispatch the associated elevator car from the dispatching floor, call registering mechanism for registering calls for elevator service for each of said plurality of floors, demand means responsive to the calls for elevator service by the call registering means for evaluating the demand for service, and means responsive to the demand means upon occurrence of a predetermined service demand and to the presence of a plurality of elevator cars at the dispatching floor for expediting the operation of one of said dispatcher devices to expedite the dispatch of a car from the dispatching floor.
